UNITED STATES PATENT OFFICE.

CHARLES L. HOUGHTON, OF WESTFIELD, MASSACHUSETTS, ASSIGNOR OF TWO-THIRDS TO MARCIENE H. WHITCOMB, OF HOLYOKE, MASSACHUSETTS, AND GEORGE E. ENO, OF SIMSBURY, CONNECTICUT.

BRAKE FOR MILL-TRUCKS.

SPECIFICATION forming part of Letters Patent No. 764,291, dated July 5, 1904.

Application filed October 3, 1903. Serial No. 176,555. (No model.)

To all whom it may concern:

Be it known that I, CHARLES L. HOUGHTON, a citizen of the United States of America, residing at Westfield, in the county of Hampden and State of Massachusetts, have invented new and useful Improvements in Brakes for Mill-Trucks, of which the following is a specification.

This invention relates to brake constructions, and especially to brakes for mill-trucks, the object of the invention being to provide a construction whereby when the tongue of the truck is in a horizontal position the brake will be inoperative, but will become set upon 15 swinging the tongue upward to a substantially perpendicular position.

In the drawings forming part of this application, Figure 1 is a plan view of a portion of the forward end of the truck and its tongue, 20 showing my improved brake devices applied thereto, the tongue being in a horizontal position. Fig. 2 is a sectional elevation of the parts shown in Fig. 1 with the tongue swung to a vertical position, the plane of the section being on line 2 2, Fig. 1.

Referring to the drawings, *a* indicates the truck-axle, and *b* the wheels. Projecting from the truck-axle, or, if preferred, its bolster, is a rigid bracket *c*, in the forward end of which the tongue *d* is pivotally supported on a pin *e*. Extending transversely of the forward end of the truck and underneath the latter are two swinging brake-arms *f*, the outer extremities of which may be provided with suitable shoes, 35 as *g*. The inner ends of the brake-arms *f* terminate at about the longitudinal center of the truck, said arms being pivoted to swing in a horizontal plane. An appropriate way of supporting these arms is to pivot them, as at 40 *h*, on the bracket *c*, though they may be elsewhere supported, if desired, in a manner which will permit their operation as below described. In the rear end of the tongue back of the pivot-pin *e* a link *i* is pivotally mounted by 45 one end, as shown in Fig. 1, its opposite end being pivotally united to the inner ends of the brake-arms *f*. Preferably the ends of these arms are provided with an elongated slot *j* and overlap with these slots in registration,

one bolt, *k*, serving to unite the two ends of 50 the brake-arms and one end of the link *i*.

From the foregoing description it will be seen that as long as the tongue *d* is horizontally disposed the truck may be moved at will without imparting any movement to the brake-arms, movement being imparted to the truck from the tongue through the rigid bracket *c* and the pin *e*, on which the tongue swings; but upon throwing the tongue upward to the position shown in Fig. 2 the link *i* will be 60 swung downward and forward beneath the pin *e*, causing the outer ends of the brake-arms to move rearwardly against the truck-wheels, locking the latter. To hold the brake set, the tongue may be locked in its vertical 65 position in any suitable manner, a convenient means being shown in the drawings, which consists in securing a loose ring *m* on the upper side of the tongue under a suitably-bent metal bar *n* and in providing on the forward end of the truck an upstanding pin *o*, suitably located to permit the ring *m* to be dropped onto the pin when the tongue is swung upward to set the brake.

Obviously the brake would operate as effectively, though with less power, if only one brake-arm were employed instead of the two shown and described herein; but the latter construction is clearly better and is preferred.

Having thus described my invention, what 80 I claim, and desire to secure by Letters Patent of the United States, is—

The combination with the tongue of a truck pivotally supported on the latter to swing in a vertical plane, of a support for said tongue secured to the truck, of brake-arms pivotally supported on said tongue-support and extending transversely of the truck, with their outer ends in proximity to the wheel, a link with 85 which the contiguous inner ends of the brake-arms are connected, said link being connected with the rear end of the tongue eccentrically to the pivotal point of the latter.

CHARLES L. HOUGHTON.
